UNITED STATES PATENT OFFICE.

CHARLES LIONEL MARCUS, OF NEW YORK, N. Y.

DESIGN FOR A BOTTLE OR SIMILAR CONTAINER.

Application filed July 5, 1924. Serial No. 10,071. Term of patent 3½ years.

To all whom it may concern:

Be it known that CHARLES LIONEL MARCUS, a citizen of the United States, and resident of the city of New York, in the county of New York and State of New York, has invented a new, original, and ornamental Design for Bottle or Similar Container, of which the following is a specification, reference being had to the accompanying drawing, forming part thereof, in which,

Fig. 1 is a vertical elevational view of a bottle or similar container embodying my new design, and

Fig. 2 is a top plan view thereof.

I claim:

The ornamental design for a bottle or similar container as shown.

Dated New York city, June 14th, 1924.

CHARLES LIONEL MARCUS.
